UNITED STATES PATENT OFFICE.

STERLING ELLIOTT, OF NEWTON, MASSACHUSETTS.

INKING MECHANISM FOR PRINTING-PRESSES.

1,036,202.

Specification of Letters Patent. Patented Aug. 20, 1912.

Application filed February 6, 1911. Serial No. 606,708.

To all whom it may concern:

Be it known that I, STERLING ELLIOTT, residing at Newton, in the county of Middlesex and State of Massachusetts, have invented an Improvement in Inking Mechanism for Printing-Presses, of which the following is a specification.

This invention relates to inking-mechanism for printing-presses, addressing-machines and the like, and has for its object the employment of an ink-roll, such for instance as shown in my application for Letters Patent #552,286. Said ink-roll comprises essentially a hollow ink-cylinder having small perforations in its cylindrical wall, and a frame-bar contained in said cylinder and adapted to work in the ink therein, having a beveled edge which terminates at or close to the perforated wall, to form a converging space between the frame bar and wall for the ink, from which the ink is forced through the perforations in minute but measured or regulated quantities, by a movement of one part relative to the other.

The present invention has for its object to arrange the frame-bar to revolve with the ink-cylinder, but at a different speed, whereby one is movable with respect to the other, to force the ink through the perforations in the cylinder. This feature of my present invention is shown as a modification in my aforesaid application, but is not therein specifically claimed.

The present invention also has for its object to provide the connecting means between the ink-cylinder and frame-bar with a clutch, whereby one part may be moved independently of the other.

The invention also has for its object to employ a positively driven distributing-roll, as a means to not only distribute the ink over the surface of the ink-roll, but also to drive said ink-roll and ink-forcing means carried by it.

The invention also has for its object to provide means to move said ink-roll out of engagement with the distributing-roll and to support it in its disengaged position.

The invention also has for its object to provide improved means to reciprocate said

distributing-roll axially while in engagement with the ink-roll, whereby the ink, which is projected through the perforations in said roll, is spread over the surface of the roll to insure an even distribution when transferred to the conveying-rolls.

Figure 1 is a side elevation of an inking-mechanism for printing presses embodying this invention. Fig. 2 is a plan view of the same. Fig. 3 is a longitudinal vertical section of the ink-roll which I prefer to employ. Figs. 4, 5, 6 and 7 are detail views of the distributing-roll and means for reciprocating it axially. Figs. 8 and 9 are detail views of the connecting-means between the ink-roll and frame-bar arranged in said roll, whereby said parts are movable one with relation to the other. Figs. 10 and 11 are details of a support for the ink-roll, whereby it may be held in or out of engagement with the distributing-roll which is employed to drive it.

The ink-roll consists of a perforated hollow cylinder *a*, see Fig. 3, having closing means at one end consisting of an end-piece *b*, provided with an outwardly extended stub-shaft *b*²; and having closing means at the opposite end consisting of an end-piece *d* having a circular hole through it which receives a removable plate *d*', provided with an outwardly extended boss *d*². A frame-bar is arranged in said hollow cylinder *a*, which is shown as bail-shaped, and comprises a bar *e* extended lengthwise and substantially from end to end of the cylinder having arms *e*', *e*', at its opposite ends, each provided with an outwardly extended gudgeon, as *e*², *e*³; and one of said gudgeons, as *e*², enters a center-hole in the end-piece *b*, and the other gudgeon, as *e*³, extends through a center-hole in the plate *d*', so that the frame-bar is radially disposed in the cylinder, and is adapted to be immersed in and work in the ink contained therein. The bar *e* is arranged close to the wall of the cylinder, and has a beveled edge, see Fig. 8, terminating at the wall of the cylinder to form a converging space between itself and said wall. As the frame-bar and cylinder are moved, one with relation to the other the ink contained in the converging space, is

forced through the small perforations in the cylinder in minute yet measured or regulated quantities. The ink-roll thus described is or may be the same as in my application before referred to.

5 h represents a distributing-roll which is secured to a shaft h' , supported by suitable bearings in which it is longitudinally or axially movable. As here shown said roll is 10 designed to be positively rotated, and to accomplish this result a belt pulley h^2 is or may be secured to one end of the shaft h' , see Fig. 4, which receives upon it a belt. Said distributing-roll is located beneath and 15 in close proximity to the ink-roll, to engage and drive said ink-roll when desired.

The distributing-roll is movable axially back and forth while in engagement with the ink-roll, and, herein, simple yet effective 20 means are shown for automatically accomplishing this result, yet my invention includes other means operating to attain the same end in substantially the same way. The means here shown consists of a worm 25 h^3 , secured to the shaft h' , which engages a worm-wheel h^4 , arranged loosely on a pivot-shaft h^5 ; an arresting-lever h^6 for said worm-wheel, pivoted at h^7 , having a tooth h^8 , at a point intermediate its length, 30 which is adapted to engage said worm-wheel to arrest it, and having its outer or free end extended toward or over the shaft h' , between one end of the worm h^3 and a collar h^9 , which is secured to said shaft. In 35 operation the shaft h' revolves the worm h^3 , and while the worm-wheel is arrested by the lever h^6 , as shown in Fig. 4, said shaft is caused to move axially in a direction toward the right until the end of the 40 worm engages the arresting-lever and moves it out of engagement with the worm-wheel, as shown in Fig. 5. The moment the worm-wheel is disengaged it is free to be turned on its pivot, and the shaft is no longer 45 caused to move in a direction toward the right, but is placed under the influence of means employed for moving it in the opposite direction, to return it to its normal position.

50 Referring to Fig. 7, wherein the returning means for the shaft h' is shown, said shaft h' is made hollow and has within it a long spiral spring h^{10} , bearing at one end against a fixed block or stop h^{12} , secured 55 to the shaft, and at the other end against a sliding pin h^{13} , which is loosely fitted into the opposite end of the shaft, and which bears against a step h^{14} , which serves as a bearing for it. The pin h^{13} maintains its 60 position at all times, but whenever the spring is permitted to extend it acts to move the shaft in a direction toward the left.

65 Return movement of the shaft is checked by the collar h^9 engaging the arresting- 65 lever and throwing it into engagement with

the worm-wheel, thereby again arresting the worm-wheel whereupon the movements above described are repeated, the spring h^{10} being compressed by the shaft h' moving toward the right.

70 In lieu of employing a spring h^{10} , arranged as here shown, other suitable means may be employed to return the shaft to its normal position.

I am aware that distributing-rolls have 75 been reciprocated axially, but not by the improved means here shown and described, which is simple and automatic in its action.

The ink contained in the ink-cylinder is very thick, so that when the frame-bar 80 which is immersed in the ink is unrestrained it will revolve with the ink-cylinder, and in order that said frame-bar may subserve its functions and force the ink through the numerous small perforations in the ink-cylinder, its movement with respect to the ink-cylinder is restrained to a limited extent, that is to say, it is adapted to revolve at a slower speed, although substantially the same results would be accomplished if re- 85 volved at a faster speed, the bevel being reversed, as in either case, a relative movement is produced whereby the ink is forced from the converging space between the frame-bar and cylinder through the perforations. It is here shown, for illustration, as moving at a slower rate of speed, and referring particularly to Figs. 8 and 9, connecting means are shown between the frame-bar and ink-cylinder whereby the 90 frame-bar is restrained but to a limited extent. Said connecting means consists of a gear-wheel g arranged on the end plate d of the ink-cylinder which engages a pinion g' of greater diameter loosely mounted and freely revoluble on a pivot-stud g^{10} , and said pinion bears a pawl g^{12} , as one member of a clutch, which engages a ratchet-toothed hub g^{13} as the other member of the clutch, arranged on a gear-wheel g^2 , which 95 is also loosely mounted on said pivot-stud g^{10} , and which is made of less diameter than the pinion g' , and said gear-wheel g^2 engages a pinion g^3 of larger diameter which 100 is secured to the gudgeon e^3 of the frame-bar. This connection forms a differential gearing between the cylinder and frame-bar. In operation, as the cylinder revolves and the frame-bar revolves with it the gear-wheel g is revolved and also the pinion g^3 , 105 but owing to the different diameters of the gear-wheels and pinions, the frame-bar will be moved at a slightly slower rate of speed, losing say at the rate of one revolution to fifteen. This variation is sufficient for the 110 purposes intended, but may be more or less as desired.

115 The clutch which is provided between the pinion g' and gear-wheel g^2 admits of one of the parts being moved independently of 120 the other, and the clutch may be of any 125 desired construction.

130

- the other to increase the supply of ink, a result which may be accomplished by engaging the hub g^{30} of the pinion g^s .
- It is not only desirable that the ink-roll shall be removable from the machine, but also shall be arranged to be moved quickly out of engagement with the distributing-roll h when desired, and as a means to accomplish this result the journals of the ink-roll occupy positions in slots i formed in the frame, see particularly Figs. 10 and 11, and when in engagement with the distributing-roll will occupy positions near the bottoms of said slots. Beneath or in close proximity to the journals of said roll a pair of cam-plates i^s , i^2 , are arranged, which are or may be secured to a suitably supported rock-shaft i^3 , and said cam-plates are adapted to be moved by rocking said shaft to lift the ink-roll out of engagement with the distributing-roll. Said cam-plates are formed with journal-bearings at their ends to provide supports for the ink-roll when in elevated position and disengaged from the distributing-roll. The rock-shaft has a finger-piece i^4 by which it may be rocked. The cam-plates have slots i^5 which receive stop-pins i^6 to limit their movements in opposite directions. In lieu of this particular means to lift the ink-roll other means may be employed.
- I claim:—
1. In an inking-device for printing-presses, an ink-roll consisting of a hollow perforated cylinder, a frame-bar contained in and extended lengthwise said cylinder and adapted to work in the ink contained therein, having a beveled edge terminating at the wall of the cylinder, to form a converging space between the frame-bar and cylinder for the ink, means to revolve said cylinder and frame bar, and differential gearing connecting the frame-bar and cylinder, whereby the speed of the frame-bar with respect to the cylinder is varied and the ink thereby forced through the perforations in the cylinder, substantially as described.
  2. In an inking-device for printing-presses, an ink-roll consisting of a hollow perforated cylinder, a frame-bar contained in and extended lengthwise said cylinder and adapted to work in the ink contained therein, having a beveled edge terminating at the wall of the cylinder, to form a converging space between the frame-bar and cylinder for the ink, means to revolve said cylinder and frame-bar, and differential gearing connecting the frame-bar and cylinder having a clutch to connect the parts thereof, whereby the speed of the frame-bar with respect to the cylinder is varied and the ink thereby forced through the perforations in the cylinder and one part permitted to be moved independently of the other, substantially as described.
  3. In an inking-mechanism for printing-presses, the combination with a positively-driven distributing-roll, of a hollow perforated ink-cylinder engaged and driven by said roll, containing means to force the ink through the perforations in said cylinder, substantially as described. 70
  4. In an inking-mechanism for printing-presses, the combination with a positively-driven distributing-roll of a hollow perforated ink-cylinder engaged and driven by said roll, and means contained in and rotated with said cylinder but at a different speed to force the ink through the perforations thereof, substantially as described. 75
  5. In an inking-mechanism for printing-presses, the combination with a positively-driven distributing-roll, of a hollow perforated ink-cylinder engaged and driven by said roll, means contained in and rotated 80 with the cylinder to force the ink through the perforations thereof, and means connecting said ink-forcing means with the cylinder whereby its movement with respect to the cylinder is varied, substantially as described. 85
  6. In an inking-mechanism for printing-presses, the combination with a positively-driven distributing-roll, of a hollow perforated ink-cylinder engaged and driven by 90 said roll, means contained in and rotated with the cylinder to force the ink through the perforations thereof, and differential gearing connecting said ink-forcing means with the cylinder, whereby its movement 95 with respect to the cylinder is varied, substantially as described. 100
  7. In an inking-mechanism for printing-presses, the combination with a positively-driven distributing-roll, of an ink-roll engaged and driven by said distributing-roll, said ink-roll consisting of a hollow perforated cylinder and a frame-bar contained in and extended lengthwise said cylinder and adapted to work in the ink contained therein, having a beveled edge terminating at the wall of the cylinder to form a converging space between the frame-bar and cylinder for the ink, and means to connect the frame-bar with the cylinder whereby movement of the frame-bar with respect to the cylinder is varied, substantially as described. 110
  8. In an inking-mechanism for printing-presses, the combination with a positively-driven distributing-roll, of a hollow perforated ink-cylinder adapted to be engaged and driven by said roll containing means to force the ink through the perforations in said cylinder, and means to move said ink-cylinder out of engagement with said roll, 115 substantially as described. 120
  9. In an inking-mechanism for printing-presses, the combination with a positively-driven distributing-roll, of a hollow perforated ink-cylinder adapted to be engaged 125

and driven by said roll, containing means to force the ink through the perforations in said cylinder, and means to move said ink-cylinder out of engagement with said roll, 5 having journal bearings for said cylinder which are brought into position to support said cylinder when disengaged from the roll, substantially as described.

10. In an inking-mechanism for printing-
10 presses, a revoluble distributing-roll, a worm on the shaft of said roll, a worm-wheel which it engages, arresting-means for said worm-wheel, means to move the shaft axially in one direction to throw the arresting-
15 means into engagement with the worm-wheel, and means operated by the shaft, when moved axially in the opposite direction, to throw the arresting-means out of engagement with the worm-wheel, substan-
20 tially as described.

11. In an inking-mechanism for printing-
presses, a revoluble distributing-roll, a worm on the shaft of said roll, a worm-wheel which it engages, an arresting-lever for said worm-wheel arranged in co-operative relation with the shaft, means to move the shaft axially in one direction to throw the arresting-lever into engagement with the worm-wheel, and means operated by the shaft when moved axially in the opposite direction to throw said arresting-lever out of engagement with the worm-wheel, substantially as described. 25

In testimony whereof, I have signed my name to this specification, in the presence of 30 two subscribing witnesses.

STERLING ELLIOTT.
